UNITED STATES PATENT OFFICE

ANNE W. CROSS, OF STOCKTON, CALIFORNIA, ASSIGNOR OF ONE-THIRD TO BURNETT CONNELL AND ONE-THIRD TO BERNARD PRIVAT

SANITARY INDIVIDUAL TELEPHONE MOUTHPIECE

Application filed December 19, 1927. Serial No. 241,215.

This invention relates to telephone mouth pieces my principal object being to provide a detachable mouthpiece of an inexpensive material so that it may be discarded after being once used; and to provide a means for properly supporting the mouth piece in operative position relative to the telephone while enabling it to be easily placed and removed by the user.

My improved device is particularly intended for use on public telephones which are used by people of all kinds and in varying conditions of ill health, some of whom speak closely into the mouth piece as is customary and are bound to leave dangerous disease germs in the mouth piece which may be transmitted to the next person using the telephone. As a result of the use of the ordinary permanently fixed and unsanitary mouthpieces, I believe that many people have undoubtedly contracted diseases who otherwise would escape.

With my improved mouthpiece such conditions cannot obtain if the individual user merely exercises the necessary caution to always insert a new mouthpiece when using the telephone.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of one form of mouthpiece and its holder as mounted in connection with a telephone.

Fig. 2 is a perspective view of the holder itself.

Fig. 3 is a perspective view of the mouthpiece.

Fig. 4 is a sectional elevation showing the mouthpiece as connected to a modified form of holder.

Fig. 5 is a side elevation of the relatively fixed member of the holder detached.

Fig. 6 is a similar view of the removable member of the holder.

Fig. 7 is a sectional elevation of still another modified form of holder and mouthpiece.

Referring now to the numerals of reference on the drawings, and particularly at present to Figs. 1-3, 1 denotes the diaphragm casing of the telephone, the front cover plate 2 of which has a tapped boss 3 in which the usual hard rubber mouthpiece is screwed. I remove this mouthpiece and in its place screw a short sleeve 4 having a shoulder 5 which limits the inward screwing movement of the sleeve. Intermediate its ends the sleeve is provided with a transverse perforated web 6. The bore of the sleeve from the web outwardly has a diverging taper or flare to wedgingly and detachably receive the inner end of the mouthpiece 7. This mouthpiece is of a shape and size approximately that of a standard mouthpiece and is preferably made of paper or other inexpensive and flexible material moulded or otherwise formed as may be best determined. The bottom 8 of the mouthpiece is freely perforated and is concave relative to the web 6, so that said web and bottom will not engage each other and no interference with sound is had if the perforations in the web and bottom do not register. The taper fit between the mouthpiece and its holder provides for ease of placement of the mouthpiece in position while insuring a relatively rigid support of the mouthpiece; and the taper or slope of the mouth piece from end to end enables them to be nested together in a compact form as is done with sanitary paper drinking cups and the like. The web in the sleeve serves as a protector for the diaphragm and prevents the same from being possibly accidentally or maliciously damaged when the mouthpiece is removed and the diaphragm is thus freely exposed.

In the form of the device above described, the sleeve is never intended to be removed. In the arrangement shown in Fig. 4 to Fig. 6, the type of mouthpiece is the same, but I employ a different holder arrangement. This holder comprises a smooth bore bushing 9 to be screwed into the boss 3. The mouth-

piece holding sleeve 10 is detachably supported by the bushing, the inner portion 10^a of the sleeve being of reduced diameter to fit the bore of the bushing and has longitudinal slits to enable said portion to be somewhat contracted and thus to have a desired wedge or press fit in the bushing.

Intermediate its ends this sleeve has a perforated web 11 and the mouthpiece 7 fits into the sleeve outwardly of the web, said sleeve having a shoulder 12 to prevent the mouthpiece from being pressed into place as far as the web. The space thus left between the web and the bottom of the mouthpiece is utilized to detachably receive a small hoop 13 over which a piece of sanitary gauze 14 or the like is stretched. With this arrangement the hoop may be removed at any time to replace the gauze and the sleeve likewise may be removed for cleaning when desired, without disturbing or unscrewing the bushing—an operation which if repeated many times would soon cause the threads to be worn out.

25 In the arrangement shown in Fig. 7, the bushing 9 is retained but the sleeve 10 is replaced by a relatively small straight sided sleeve 15. The outer portion of this sleeve is adapted to fit inside the mouthpiece 7^a, whose bottom 8^a is depressed some distance into the mouthpiece as shown so as to enable the sleeve to be inserted sufficiently to provide a firm support for the mouthpiece, and also limiting the extent to which the sleeve may project into the mouthpiece.

From the foregoing description it will be readily seen that I have produced such a device as substantially fulfills the objects of the invention as set forth herein.

40 While this specification sets forth in detail the present and preferred construction of the device, still in practice such deviations from such detail may be resorted to as do not form a departure from the spirit of the invention, 45 as defined by the appended claims.

Having thus described my invention what I claim as new and useful and desire to secure by Letters Patent is:

1. A sanitary telephone mouthpiece structure, said telephone having an orificed diaphragm-casing cover, comprising a rigid member to be secured to said cover and to project outwardly therefrom about the orifice and a flexible mouthpiece arranged to have 55 detachable frictional engagement with and be supported at its inner end by said member.

2. A sanitary telephone mouthpiece structure, said telephone having a diaphragm-casing cover, provided with a tapped orifice, comprising a bushing to be screwed into said orifice, a sleeve to be detachably pressed into the bushing and to project outwardly therefrom, and a mouthpiece to be supported by the sleeve and having a detachable press-fit therewith.

3. A sanitary telephone mouthpiece structure, said telephone having an orificed diaphragm-casing cover and a rigid member secured to and projecting outwardly from said cover, comprising a flexible mouthpiece element to detachably project at its inner end over the outer end of said member with a frictional fit.

4. A sanitary telephone mouthpiece structure, said telephone having an orificed diaphragm-casing cover and a member secured to and projecting outwardly from said cover, comprising a mouthpiece element to detachably fit over the outer end of said member, and a cross wall in said element a predetermined distance from the inner end thereof to engage the outer end of the telephone member and limit the extent to which said element may project over the member.

5. A sanitary telephone attachment comprising a mouthpiece element of thin bendable material, said material at the inner end of the element being doubled back upon itself inside the element for a certain distance and at its inner end being formed with a transverse perforated wall, and a rigid member to be mounted on and project outwardly from a telephone diaphragm-casing and adapted to frictionally fit in the doubled-back portion of the mouthpiece element.

In testimony whereof I affix my signature.

ANNE W. CROSS.
